UNITED STATES PATENT OFFICE.

ARTHUR B. McCORD, OF OAK PARK, ILLINOIS, ASSIGNOR TO McCORD SILENT SLEEVE MOTORS CO., OF CHICAGO, ILLINOIS, A CORPORATION OF DELAWARE.

VALVE-OPERATING MECHANISM.

1,282,896.

Specification of Letters Patent. Patented Oct. 29, 1918.

Application filed February 18, 1918. Serial No. 217,961.

To all whom it may concern:

Be it known that I, ARTHUR B. McCORD, a citizen of the United States of America, residing at Oak Park, in the county of Cook and State of Illinois, have invented certain new and useful Improvements in Valve-Operating Mechanism, of which the following is a specification.

My invention relates to improvements in valve operating mechanism, particularly for internal combustion engines, and the objects of my improvement are:

First, to produce automatically operable means to control the amount of fuel intake. Second, the production of mechanism for automatically taking up possible wear of working surfaces in addition to the performance of the functions of a governor.

An important feature of my invention is the construction and arrangement of parts to act as a governor to prevent too rapid acceleration of the sleeve valve and to automatically take care of the expansion and contraction of the parts caused by excessive heat and cold.

With the foregoing and other objects in view, my invention consists in the novel features and in the novel combination and arrangement of the parts hereinafter fully described, illustrated in the accompanying drawings forming a part of this specification, and particularly pointed out in the claims hereunto appended; it being understood that changes, variations and modifications in the details of the invention within the scope of the claims, may be resorted to without departing from the spirit or sacrificing any of the advantages thereof.

In the drawings,

Figure 1 is a central section of a single cylinder engine with a sleeve valve partly in section showing in elevation valve means for reciprocating the sleeve valve,

Fig. 2 is an end elevation of valve operating mechanism fixed to the sleeve valve and in operative relation to a cam-shaft,

Fig. 3 is a sectional view on line 3-3 on Fig. 1,

Fig. 4 is a section on line 4-4 on Fig. 2,

Fig. 5 is a sectional view on 5-5 on Fig. 2,

Fig. 6 is a perspective of the upper cam-roller shaft,

Fig. 7 is a similar view of the lower cam-roller shaft.

55

Similar numerals and letters refer to similar parts throughout the several views.

In accordance with my invention, when applied to an internal combustion engine, in the chosen embodiment, there is provided a fixed cylinder 8, which is cut away at 8' to afford clearance for means to reciprocate the sleeve valve 9, intake ports 10 and exhaust ports 11 through the fixed cylinder, and intake ports 12 and exhaust ports 13 through 65 the sleeve valve 9, adapted to register timely and sufficiently in operation of the engine.

Within the sleeve valve 9 is the usual piston 14 suitably connected with the rod 15 in operative relation with the crank 16 of crank shaft 17 which carries sprocket 18 which meshes with chain 19 in mesh with sprocket 20 fixed to cam-shaft 21 and also in mesh with sprocket 22 on magneto shaft 23. The cam-shaft 21 is mounted for movement 75 one half as fast as the crank-shaft 17.

The reference numeral 24 denotes the intake manifold and the numeral 25 designates the exhaust manifold.

The sleeve valve 9 near one end and externally thereof and preferably integral therewith is formed with parallel bosses 26 and 27 to which is detachably secured a bracket or yoke member 28 by any preferred means, as herein shown by screws 29 at one end and 35 30 at the other end. It will be noted the free ends of the member 28 are formed with outwardly extending flanges 31, 32, the flange 31 engaging with the inner edge of boss 26 and the flange 32 engaging with the corresponding inner edge of boss 27, and serve to take the strain off the securing means 29, 30. Preferably the member 28 is drop forged. A shaft 33 is secured to the upper end of the bracket 28 and has hole 35' therethrough and carries roller 34 which contacts with cam 35.

Taper pin 36 extends through the shaft 33 and the upper part of bracket 28 and prevents rotation of said shaft. A shaft 37 is 100 formed with an eccentric portion 38 and extends through the lower end of the bracket 28 to receive the roller 39 on the eccentric part 38. The roller 39 contacts with cam 40. To the shaft 37 is secured a curved governing lever or arm 41, having a taper pin 42

90

105

through the arm 41 that engages the shaft 37 at 43 to prevent turning of the shaft 37 relative to the lever 41. Fixed to the free end and extending beyond the governing lever 41 is a resilient element 44 in operative relation near its apertured end 45 with adjusting or tension means 46 which has threaded engagement at 47 with the bracket 28, near the free end of the resilient element 44 there is provided a plurality of fins 48 between which is disposed the head 49 of the bolt 46 to prevent unturning movement of the adjustment means 46 and to maintain a definite and proper tension of the lever 41. It will be noted that by means of the eccentric portion 38 the roller 39 is held in contact with the cam 40 by the tension of the resilient element 44, which may be changed at will, and the variations in the dimensions of parts caused by expansion by heat and contraction by cold are taken care of automatically.

The shaft 33 has an oil groove 51 and the shaft 37 has a similar oil groove 52 formed therein.

My governing device comprises bracket 28 in which is mounted shaft 37 having an eccentric part 38 which carries the roller 39 in contact with the cam 40. The shaft 37 has fixed thereto the governing lever 41 at one end of which is the resilient element 44 in operative engagement with the tension means 46.

The resilient element 44 prevents the intake ports 10 from opening its full stroke at high speed. A further advantage of the element 44 is to provide a take up in case of wear by means of bolts 46. The element 44 serves as a bumper to prevent excessive noise and wear on roller 39 and thus acts as a governor for the intake valve. When the engine throttle is suddenly opened the pressure against the roller 39 is so great the resilient element 44 will yield and instantly the roller 39 will be in position sufficiently to prevent the intake ports fully opening.

At low speed the element 44 is not flexed at all.

Adjustment to limit maximum speed of the engine is accomplished by changing the degree of force required to flex the resilient element 44. Tightening the bolt 46 increases the tension and loosening the bolt 46 diminishes the resistance of the element 44. The result of such adjustment is to control the speed of the engine by limiting the quantity of gas that may pass through the intake ports into the engine cylinder for combustion.

In operation when the engine throttle is opened too quickly the cam 40 will strike the roller 39, with such force as to cause the governing lever and its resilient element 44 to yield and flex so that the arm 41 and the element 44 will take the position indicated

by the dotted line 50, thereby increasing the distance between cam-shaft 21 and the cam roller 39, and thus preventing the intake ports 12 of the sleeve 9 fully registering with the intake ports 10 of the fixed cylinder 8, and thus limiting the fuel charge to the engine.

By showing and describing one embodiment of my invention I do not intend to restrict the range of equivalents not made necessary by the prior state of this art.

Having thus fully described my invention, what I claim as new, and desire to secure by Letters-Patent is:

1. In mechanism of the class described, the combination with a sleeve valve having a bracket fixed thereto and cam means for reciprocating the sleeve valve, of a governing lever including a shaft having an eccentric portion and a cam-roller thereon at one end and at the other end said lever having a resilient connection with said bracket to control the speed of the engine by limiting the quantity of gas that may pass through the intake ports into the engine cylinder. 90

2. In an internal combustion engine, the combination with a sleeve valve having a bracket fixed thereto and cam means to reciprocate the sleeve valve, of a governing lever including a shaft having an eccentric portion and a cam-roller thereon and at one end having a resilient connection with said bracket and tension means carried by said bracket.

3. In an internal combustion engine, the combination with a sleeve valve and a bracket fixed thereto carrying a cam-roller and a fixed shaft therefor and a shaft having an eccentric portion and a cam roller thereon and a cam shaft having a pair of cams fixed thereto in operative relation to said cam-rollers, of a governing lever fixed to said shaft having an eccentric portion at one end and at the other having a resilient connection with said bracket. 110

4. In mechanism of the class described, the combination with a fixed cylinder having intake and exhaust ports therethrough, a sleeve valve provided with intake and exhaust ports adapted to be caused to register with the ports in the fixed cylinder, a bracket fixed to the sleeve valve and carrying a fixed shaft and a cam-roller thereon and a shaft having an eccentric portion and a cam-roller thereon, and a cam-shaft having a pair of cams fixed thereto and in operative relation to said cam rollers, of a governing lever fixed at one end to said shaft having an eccentric portion and at the other end having yielding connection with said bracket. 115

5. In an internal combustion engine, the combination of a fixed cylinder having intake and exhaust ports therethrough, a sleeve valve provided with intake and exhaust 130

ports adapted to be caused to register with said ports in the fixed cylinder, a cam shaft having a pair of cams fixed thereon, a bracket fixed to the sleeve valve and carrying a fixed shaft and a cam roller in contact with one of said cams and a shaft having an eccentric portion, and a governing lever fixed to said last named shaft and a cam-

roller on said eccentric portion in contact with the other of said cams, means to actuate the cam shaft, resilient means and tension means between the governing lever and said bracket. 10

In testimony whereof I affix my signature.

ARTHUR B. McCORD.
